US0D1034963S

(12) **United States Design Patent** (10) **Patent No.:** **US D1,034,963 S**
(45) **Date of Patent:** **** Jul. 9, 2024**

(54) **CANNULA**

(71) Applicant: **EUROSETS S.r.l.**, Medolla (IT)

(72) Inventors: **Marco Piccinini**, Medolla (IT); **Luca Caleffi**, Medolla (IT)

(73) Assignee: **EUROSETS S.R.L.**, Medolla (IT)

(**) Term: **15 Years**

(21) Appl. No.: **35/516,743**

(22) Filed: **Mar. 31, 2022**

(80) **Hague Agreement Data**

Int. Filing Date: **Mar. 31, 2022**

Int. Reg. No.: **DM/222554**

Int. Reg. Date: **Mar. 31, 2022**

Int. Reg. Pub. Date: **Mar. 31, 2023**

(30) **Foreign Application Priority Data**

Oct. 1, 2021 (EM) 008713192-0003

(51) **LOC (14) Cl.** **24-02**

(52) **U.S. Cl.**

USPC **D24/112**

(57) **CLAIM**

The ornamental design for a cannula, as shown and described.

DESCRIPTION

Figure 1.1 is a perspective view;

Figure 1.2 is a top view thereof;

Figure 1.3 is a bottom view thereof;

Figure 1.4 is a front view thereof;

Figure 1.5 is a rear view thereof;

Figure 1.6 is a right side view thereof; and

Figure 1.7 is a left side view thereof.

The features shown in broken lines are for the purpose of illustrating portions of the cannula that form no part of the claimed design.

1 Claim, 7 Drawing Sheets
